UNITED STATES PATENT OFFICE.

HENRY K. SPENCER, OF DORCHESTER, MASSACHUSETTS, ASSIGNOR TO THE BLANCHARD MACHINE COMPANY, OF CAMBRIDGE, MASSACHUSETTS, A CORPORATION OF MASSACHUSETTS.

MOUNTING OF ABRASIVE WHEELS.

1,079,304.

Specification of Letters Patent.

Patented Nov. 18, 1913.

Original application filed September 21, 1911, Serial No. 650,563. Divided and this application filed December 16, 1912. Serial No. 736,909.

To all whom it may concern:

Be it known that I, HENRY K. SPENCER, a citizen of the United States, and a resident of Dorchester, in the county of Suffolk and State of Massachusetts, have invented an Improvement in Mounting of Abrasive Wheels, of which the following description, in connection with the accompanying drawings, is a specification, like characters on the drawings representing like parts.

This invention relates to the mounting of abrasive wheels, and will be best understood by reference to the following specification, when taken in connection with the accompanying illustration of one specific embodiment thereof, while its scope will be more particularly pointed out in the appended claims.

20 This application is a division of my prior, co-pending application, Serial No. 650,563, filed September 21, 1911.

The drawing shows in central vertical section an abrasive wheel and mounting therefor, embodying my invention.

Referring to the drawing, and to the illustrative embodiment of my invention there shown, 1 is a spindle, to which a usual face plate 2 is secured in any suitable manner. 30 An abrasive wheel 3, which may be of any usual or desired form, is secured to the face plate in a novel manner. The abrasive wheel 3 is herein shown as formed with straight sides, that is to say, its periphery is cylindrical. Herein, the wheel is secured to a retaining ring 4, which in turn is secured to the face plate 2. The retaining ring 4 is provided with a flange 5, which overlies the edge of the wheel, and is tapered with reference thereto, so as to provide an angular space which is filled with cementitious material 6, such for example as ordinary Portland cement.

45 While the retaining ring may take other forms, the angular space just referred to is preferably formed by providing the ring internally with a recess 7, having a circumferential surface 8, which is herein tapered or inwardly widened. Preferably, the end 50 of the abrasive wheel is first covered with a thin layer of cement, and the wheel is then placed in the ring, this thin layer of cement being used for the purpose of level-

ing, or truing, the wheel so that its face shall lie in a plane at right angles to the axis of the spindle 1. The cement filling 6 is then inserted, and the same mass allowed to harden. This secures the wheel to the ring by means of a cemented lockjoint, which holds the wheel securely in place. Owing to the porous granular nature of the abrasive substance of the wheel, the Portland cement, when hardened, adheres very firmly thereto, but naturally does not adhere firmly to the surface of the retaining ring, which is therefore made of such form as to interlock with the cement filling and effectually prevent the wheel, with its tapered ring of cement, from becoming dislodged. If desired, the surface 8 may be roughened, so that the cement will bond thereto. This roughening may take any practical form, but herein is produced by giving the turning, or boring tool a coarse feed, so that it will produce a shallow groove of generally helical form. This mode of mounting the wheel obviates the use of clamping devices, which would naturally strain the wheel, and tend to cause it to break. Herein, the retaining ring is secured to the face plate by a plurality of screws 9, by the use of which it is possible to remove the retaining ring and wheel, and substitute other similar wheels suited to the character of the work. When the wheel is worn out, the cement and remnants of the wheel may be chipped out, and the retaining ring used again for another wheel.

While I have herein shown and described one embodiment of my invention for illustrative purposes, and have disclosed and discussed in detail the construction and arrangement incidental to one specific application thereof, it is to be understood that the invention is limited neither to the mere details or relative arrangement of parts nor to its specific embodiment herein shown, but that extensive deviations from the illustrated form or embodiment of the invention may be made without departing from the principles thereof.

Having thus described my invention, what I claim and desire by Letters Patent to procure is:—

1. The combination with a grinding wheel, of a driving spindle therefor, a face

plate, and means including a cemented lock-joint attachment for securing the grinding wheel to the face plate.

2. The combination with a driving member, a grinding wheel, and a holding device for securing the wheel to the driving member, said device having a cement-filled joint between the same and the circumferential surface of the wheel.
- 10 3. The combination with a grinding wheel, of a face plate, a retaining ring having a tapered wall adapted to overlap the wheel, and a cement filling between the wheel and the wall.
- 15 4. The combination with a driving member, of a face plate, a retaining ring, and a grinding wheel having a circumferential surface cemented to the retaining ring.
5. The combination with an abrasive
- 20 wheel, of a body of cementitious material adhering to the periphery of said wheel, and a holder with which said cementitious material interengages.
6. The combination with an abrasive

wheel, of a holder provided with a lateral recess, and a body of cementitious material adhering to the periphery of said wheel and extending laterally into said recess.

7. The combination of holding means having an inwardly widened recess, a wheel extending into said recess, and a body of cementitious substance adhering to the sides of said wheel, and engaging the sides of said recess.

8. The combination with a wheel having a cylindrical surface, a holder provided with tapered sides, and a body of cementitious substance adhering to the cylindrical surface of said wheel and engaging the sides of said recess.

In testimony whereof, I have signed my name to this specification, in the presence of two subscribing witnesses.

HENRY K. SPENCER.
